(57) **CLAIM**

The ornamental design for a smartphone mount for bicycle, as shown and described.

DESCRIPTION

FIG. 1 is a perspective view of smartphone mount for bicycle showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof in a different position. The broken lines shown illustrate portions of the smartphone mount for bicycle that form no part of the claimed design.
